HIGH-FREQUENCY VACUUM TUBE
CIRCUIT

Howard C. Lawrence, Jr., Haddonfield, N. J., assignor to Radio Corporation of America, a corporation of Delaware

Application October 28, 1943, Serial No. 508,045

19 Claims. (Cl. 250—36)

1

This invention relates to ultra high frequency oscillator circuits, and particularly to vacuum tube oscillators generating oscillations higher than 300 megacycles.

Among the objects of the present invention are: To provide an ultra high frequency electron discharge device oscillator having anode and cathode tuned circuits which are shielded from each other within the device and individually shielded externally of the device; to provide a grounded grid electron discharge device oscillator of ultra high frequencies whose anode and cathode electrodes have separate tunable circuits of distributed inductance and capacity extending from opposite sides of the device but coupled together by means of a selective feed back loop; to provide a grounded grid electron discharge oscillator of ultra high frequencies whose anode and cathode electrodes each have a shielded tunable circuit of distributed constants and of a length which is a multiple of and greater than one quarter of the length of the communication wave, these tunable anode and cathode circuits being coupled together by a tunable selective feed back circuit.

A more detailed description of the invention follows in conjunction with drawings, wherein:

Figure 1 shows a circuit diagram partly schematic and partly mechanical of the ultra high frequency oscillation generator of the invention;

Figure 2 shows the essential details of the mechanical construction of the oscillation generator of Figure 1; and

Figure 3 is a section along line 3—3 of Figure 2.

Referring to Figure 1 in more detail, there is shown an ultra high frequency generator comprising a pair of vacuum tubes 10 and 11 mounted in and supported by a metallic plate 12. This metallic plate is provided with a pair of apertures 13, 13 for accommodating the envelopes of the vacuum tubes. The grids of the tubes 10 and 11 are directly connected to the metallic plate 12, which in turn is grounded. It will thus be seen that the grid of each tube and associated mounting electrostatically shields the anode and cathode and their associated circuits from each other. A tunable parallel conductor circuit composed of hollow conductors 14 connect the anodes of the two tubes together in push-pull relation. The ends of conductors 14 at 15 are in telescopic relation to the other portions of the conductors in order to provide adjustment of the lengths of these conductors for tuning purposes. Putting it in other words, we have essentially a collapsible end 15 for tuning the anode circuit. Another pair of hol-

10 low conductors 16 forms a tunable circuit between the cathodes of the tubes. The conductors 16 are directly connected together by means of a short circuiting disc 17 forming the bottom part of an open metallic can-like arrangement 18. The filaments of the two tubes 10 and 11 are supplied with heating currents through wires extending within the interiors of the hollow conductors 16 and connected to the secondary winding of a suitable filament supply transformer 19 whose primary winding is connected to a low frequency alternating current filament heating source. The anodes of the two tubes 10 and 11 are supplied with a suitable positive polarizing potential from conductor 20 which is connected to the upper adjacent ends of the conductors 14 of the anode tuned circuit. The cathode tuning circuit is tunable by moving the can 18 up or down along the lengths of the conductors 16 by means of a suitable rod connected to plate 17. The anode and cathode tuned circuits 14 and 16, respectively are separately shielded by hollow metallic semi-circular sheets represented diagrammatically in Figure 1 by means of the dash lines 21. It will thus be seen that the anode and cathode tuned circuits are shielded from each other externally of the vacuum tubes 10 and 11 by sheets 21 and also shielded from each other electrostatically by means of the grounded grids which are directly connected to the metallic disc-like plate 12. The can 18, it should be noted, is open at the end nearest the cathodes. Can 18 is separated by an air gap from the shield 21 and is capacitively coupled to the shield.

30 In order to provide feed-back between the anode and cathode circuits, there is provided a selective feed-back circuit in the form of an S-shaped conductor comprising loops 30 and 31. It will be seen that loop 30 is above the metallic plate 12 while the loop 31 is below the metallic plate 12, both of these loops being connected together through an aperture 32 in the plate 12. The midpoint of the feed-back conductor is connected to the central conductor of a concentric line 33. The inner and outer conductors of this concentric line 33 are adjustable in length by means of a slider 34. The effective length of coaxial line 33 measured between slider 34 and the midpoint of the selective feed-back circuit 30, 31 is more than one-quarter of a wavelength at the operating frequency and hence acts as a capacity reactance for certain frequencies of operation. The total length of the loops 30 and 31 is physically less than one-half wavelength, but by means of the tunable capacity reactance constituted by the coaxial line 33, the capacitance of this line tunes the feed back circuit to one-half wavelength. While the effective length of line 33 is mentioned as being such that it is capacitative at certain frequencies of operation,

it should be understood that it may be capacitive or inductive depending upon what is needed to tune the feed back loop. This would mean that the stub may be of a length up to one-half wavelength instead of the one-quarter wavelength mentioned above. The feed back loop may be longer than one-half wavelength but tuned by an inductive reactance to be electrically one-half wavelength at the operating frequency. The loops 30 and 31 are made in the form of an S in order to assure the fact that the voltage fed back to the cathode circuit is 180° out-of-phase relative to the alternating current cathode potential. These opposite halves of the feed back conductor are 180° out-of-phase insofar as the magnetic field is concerned. The distance between the metallic plate 12 and each of the short circuiting conductors 15 and 17 of the anode and cathode tuned circuits is electrically three-quarters of a wavelength at the operating frequency.

The output circuit includes a metallic loop 24 which is arranged above the plate 12 for coupling to the anode tuned circuit. One end of the output loop 24 is connected directly to the plate 12 while the other end extends down through an aperture 35 for connection to the inner conductor of a concentric transmission line 36. Concentric transmission line 36, which connects the output loop 24 to a suitable utilization circuit such as an antenna, is shown provided with impedance matching stubs 37, 37 spaced one-quarter of a wavelength apart. A cathode bias resistor 40 is connected between ground and that end of the cathode conductor 16 farthest removed from the vacuum tubes. In the operation of the system of Figure 1, the metallic can 18 for tuning the cathode tuned circuit serves as one terminal of a condenser whose other terminal comprises the grounded metallic shield 21.

The lengths of the anode and cathode tuned circuits, which are here shown to be electrically (although not necessarily mechanically) three-quarters of a wavelength long, enable the attendant to tune the circuits at the extremely high frequencies at which the oscillator is capable of functioning. The use of multiple quarter wavelength lines is made possible by the selective feature of the feed back circuit. The selective feed back circuit comprising the loops 30 and 31 in the form of an S is tuned to the desired oscillation frequency by means of the variable capacitive reactance comprising the tunable coaxial line 33, thus controlling the frequency at which the oscillator functions. Putting it in other words, oscillations occur at the frequency of the feed back circuit only.

The oscillator of Figure 1 can be operated anywhere in the range from 350 to 1400 megacycles with anode voltages supplied to lead 20 anywhere in the range from 300 volts to 15,000 volts. Obviously, if the circuit of Figure 1 is to be operated continuously, the anode voltages would be somewhere near the 300 volt figure, whereas if the oscillation generator of Figure 1 is to be used for pulse operation, for extremely short intervals of the order of a microsecond or so, the anode voltage may be in the upper regions near 15,000 volts. By means of the arrangement of Figure 1, it is possible when using pulsing methods to obtain an output of at least 350 kilowatts employing an anode voltage of around 15,000 volts. Such pulse operation is obtainable by interrupting the anode voltage supply at the rate at which it is desired to produce pulses of high frequency energy.

Figure 2 shows a mechanical construction of the ultra high frequency oscillation generator of Figure 1. The oscillator is shown with the two upper halves of the anode circuit shielding system separated and with one-half of the lower cathode circuit shielding system missing, to simplify the drawings. The metallic plate 12 shown in more detail in Figure 3 is hidden by means of the rounded metallic sheet 50. Sheet 50 is provided with upper and lower shoulders 51 for accommodating and supporting the semi-cylindrical shields 21, 21. The shields for the anode and cathode tuned circuits each comprise two halves which are screwed together at the apertures 52. One-half of the shield for the anode and the cathode tuned circuits is shown connected to the metallic sheet 50. The other half of the shield 21 for the cathode tuned circuit is provided in the complete assemblage but is not shown in order not to complicate the drawings. It should be understood at this time that the parallel transmission line circuit comprising the anode conductors 14 is a cross between a concentric line and a parallel conductor circuit by virtue of the fact that the metallic case 21, 21 enclosing this line is an essential part of the anode circuit and is not merely a shield. The coaxial line 33 for tuning the selective feedback circuit is shown provided with a plunger 53 for adjusting the position of the slider 34 (note Fig. 1).

The cathode can-like slider 18 for tuning the cathode circuit is shown provided with a metallic rod 54 connected to the plate 17 for adjusting the position of the can 18 in tuning the cathode circuit. The bottom ends of the conductor 16 of the cathode tuned circuit are connected together by means of a metallic plate 55 mounted in turn upon an insulator board 56. It should be noted that the plate 55 to which the cathode conductors 16 are connected is not connected to the shield 21. It should also be noted that the can 18 is separated by an air space from the shield 21. The top of the shield 21 for the anode tuned circuit is open to enable the circulation of cooling fluid. This cooling fluid in the form of air from a suitable blower is supplied to the interior of the shields 21 both above and below the metallic dividing plate 12 by means of a rubber conduit 57 and air vents 58.

The conductors of the anode tuned circuit are connected to the anodes of the vacuum tubes 10 and 11 by means of metallic flanges 60. That portion of each of the conductors 14 of the anode circuit which is nearest the anode of the tubes 55 is cut away and provided with a metallic mesh-like sieve 61 for enabling air to flow freely therethrough.

The preferred type of vacuum tube to be used in the invention is one having an anode provided with a multiplicity of anode fins for cooling purposes. It is important that the grid of the tube do a good shielding job between the cathode and anode. One such tube which has been used is the RCA A-2212 tube shown very generally in Figure 3, which is a cross section of Figure 2 along the line 3-3. The anode fins are shown as horizontal metallic rings 62. The grid, anode and cathode electrodes are arranged concentrically within the tube envelope. The grid extends downward and is connected by means of a metallic flange 63 to the plate 12. The cathode extends below the flange 63 and is connected to the conductor 16 of the cathode tuned circuit. Although the anode fins of the vacuum tube have been shown to be horizontal, it should be under-

stood that, if desired, the anode cooling fins may be arranged radially.

One advantage of the present invention is that the oscillator is capable of producing considerably higher frequencies than can be obtained by conventional vacuum tube oscillators employing one-quarter wavelength sections of line as frequency controlling elements. Applicant's longer lines, which are an odd multiple, greater than unity, of a quarter wavelength, provide lengths sufficiently great to enable adjustment of the tuned circuits at the extremely high frequencies desired, and the selective feed back circuit with its variable tuning reactance permits a control of the frequency of the oscillation generator at values considerably higher than those obtainable by conventional circuits.

It should be understood that although the can-type of shorting bar 18 has been shown only in connection with the cathode line, such can-type of shorting bar may also be used on the anode line as well where the voltages allow such operation. It should also be understood that the term "ground" used in the appended claims is not limited to an actual earthed connection, but includes any point or surface of zero or fixed radio frequency potential.

What is claimed is:

1. An ultra high frequency electron-discharge device system comprising a tube having a cathode, an anode and a grid, individual tunable resonant circuits for said cathode and anode, means external of said tube for shielding said resonant circuits from each other, a direct conductive connection from said shield to said grid, a feedback loop magnetically coupling said resonant circuits together, and a connection from the center of said loop to said shield.

2. An ultra high frequency oscillator comprising a vacuum tube having a cathode, an anode, and a grid, individual tunable resonant circuits for said cathode and anode, means external of said tube for shielding said resonant circuits from each other, a direct conductive connection from said shield to said grid, and a tunable feedback loop magnetically coupling said tuned circuits together.

3. An ultra high frequency oscillator comprising a vacuum tube having a cathode, an anode and a grid, individual tunable resonant circuits for said cathode and anode, means external of said tube for shielding said resonant circuits from each other, a direct conductive connection from said shield to said grid, a feedback loop magnetically coupling said tuned circuits together, and a variable reactance for tuning said loop to the frequency of operation of said oscillator.

4. An ultra high frequency oscillator comprising a vacuum tube having a cathode, an anode and a grid, said anode and cathode extending from opposite ends of the envelope of said tube, individual tuned circuits for said anode and cathode extending on opposite sides of said tube, a shield intermediate said tuned circuits and connected to said grid, individual shields for said tuned circuits, a selective feedback circuit extending through an aperture in said first shield and feeding back voltage to said cathode tuned circuit which is 180° out-of-phase relative to the alternating cathode potential, said feedback circuit having a tunable element.

5. An ultra high frequency oscillator comprising a vacuum tube having a cathode, an anode and a grid, said anode and cathode extending

from opposite ends of the envelope of said tube, individual tuned circuits for said anode and cathode extending on opposite sides of said tube, a shield intermediate said tuned circuits and connected to said grid, individual shields for said tuned circuits, a selective feedback circuit extending through an aperture in said first shield and feeding back voltage to said cathode tuned circuit which is 180° out-of-phase relative to the alternating cathode potential, said feedback circuit being an S-shaped conductor opposite halves of which are 180° out-of-phase for the magnetic field, and a variable reactance connected to the midpoint of said S-shaped conductor.

15 6. An oscillator in accordance with claim 5, wherein said S-shaped conductor has an overall equivalent electrical length less than one-half wavelength but is tunable by said reactance to be electrically one-half wavelength at the operating frequency.

7. An ultra high frequency oscillator comprising a vacuum tube having a cathode, an anode and a grid, individual tunable resonant circuits for said cathode and anode, means external of said tube for shielding said resonant circuits from each other, a direct conductive connection from said shield to said grid, a feedback loop magnetically coupling said tuned circuits together, and a variable reactance for tuning said loop to the frequency of the operation of said oscillator, said tunable resonant circuits each having an effective length equal to an odd multiple, greater than unity, of one-quarter wavelength at the operating frequency.

25 8. An ultra high frequency oscillator comprising a vacuum tube having a cathode, an anode and a grid, said anode and cathode extending from opposite ends of the envelope of said tube, individual tuned circuits for said anode and cathode extending on opposite sides of said tube, said individual tuned circuits having substantially uniformly distributed constants and being each an odd multiple, greater than unity, of one-quarter of a wavelength at the opening frequency, a shield intermediate said tuned circuits and connected to said grid, individual shields for said tuned circuits, a selective feedback circuit extending through an aperture in said first shield and feeding back voltage to said cathode tuned circuit which is 180° out-of-phase relative to the alternating cathode potential, said feedback circuit being an S-shaped conductor opposite halves of which are 180° out-of-phase for the magnetic field, and a variable capacitive reactance connected to the midpoint of said S-shaped conductor.

30 9. An ultra high frequency oscillator comprising a pair of vacuum tubes each having an anode, a cathode and a grid, a tuned circuit of substantially distributed constants connecting said anodes together, a tuned circuit of substantially distributed constants connecting said cathodes together, means electrostatically shielding the anode and cathode of each tube from each other, means external of said tubes for shielding said tuned circuits from each other, and a selective feedback circuit coupling said two tuned circuits, said feedback circuit including a variable reactance for tuning the same to the frequency at which said oscillator should function.

35 10. An ultra high frequency oscillator comprising a pair of vacuum tubes each having an anode, a cathode and a grid, a parallel conductor tuned circuit of substantially distributed constants con-

necting said anodes together, a parallel conductor tuned circuit of substantially distributed constants connecting said cathodes together, a metallic shield connecting said grids together, a connection from said shield to ground, means external of said tubes for shielding said tuned circuits from each other, and a selective feedback circuit coupling said two tuned circuits, said feedback circuit including a variable reactance for tuning said feedback circuit, said variable reactance comprising an adjustable coaxial line whose effective length is less than one-half wavelength at the operating frequency.

11. An ultra high frequency oscillator comprising a pair of vacuum tubes each having an anode, a cathode and a grid, a tuned circuit of substantially distributed constants connecting said anodes together, a tuned circuit of substantially distributed constants connecting said cathodes together, means electrostatically shielding the anode and cathode of each tube from each other, means external of said tubes for shielding said tuned circuits from each other, and a selective feedback circuit coupling said two tuned circuits, said feedback circuit including an S-shaped conductor opposite halves of which are 180° out-of-phase for the magnetic field and a variable capacitive reactance connected to the midpoint of said S-shaped conductor for tuning the selective circuit to the frequency at which said oscillator should function.

12. An ultra high frequency oscillator comprising a pair of vacuum tubes each having an anode, a cathode and a grid, a parallel conductor tuned circuit of substantially distributed constants connecting said anodes together, a parallel conductor tuned circuit of substantially distributed constants connecting said cathodes together, means electrostatically shielding the anode and cathode of each tube from each other, means external of said tubes for shielding said tuned circuits from each other, and a selective feedback circuit coupling said two tuned circuits, said feedback circuit including an S-shaped conductor opposite halves of which are 180° out-of-phase for the magnetic field and a variable reactance connected to the midpoint of said S-shaped conductor for tuning the selective circuit to the frequency at which said oscillator should function, said reactance comprising an adjustable coaxial line whose effective length is less than one-half wavelength at the operating frequency.

13. An ultra high frequency oscillator comprising a vacuum tube having a cathode, an anode and a grid, individual tunable resonant circuits for said cathode and anode, means external of said tube for shielding said resonant circuits from each other, a direct conductive connection from said shield to said grid, a feedback loop magnetically coupling said tuned circuits together, and a variable capacitive reactance for tuning said loop to the frequency of operation of said oscillator.

14. An ultra high frequency oscillator comprising a pair of vacuum tubes each having an anode, a cathode and a grid, a parallel conductor tuned circuit of substantially distributed constants connecting said anodes together, a parallel conductor tuned circuit of substantially distributed constants connecting said cathodes together, means electrostatically shielding the anode and cathode of each tube from each other, means exter-

nal of said tubes for shielding said tuned circuits from each other, and a selective feedback circuit coupling said two tuned circuits, said feedback circuit including a variable capacitive reactance for tuning said feedback circuit, said variable capacitive reactance being composed of an adjustable coaxial line whose effective length is more than one-quarter wavelength at the operating frequency.

15. An ultra high frequency oscillator comprising a pair of vacuum tubes each having an anode, a cathode and a grid, a tuned circuit of substantially distributed constants connecting said anodes together, a tuned circuit of substantially distributed constants connecting said cathodes together, means electrostatically shielding the anode and cathode of each tube from each other, means external of said tubes for shielding said tuned circuits from each other, and a selective feedback circuit coupling said two tuned circuits, said feedback circuit including a variable reactance for tuning said feedback circuit, said variable reactance comprising an adjustable coaxial line whose effective length is less than one-half wavelength at the operating frequency.

16. A radio frequency oscillator comprising a vacuum tube having a cathode, an anode and a grid, individual tuned resonant circuits for said anode and cathode located on opposite sides of said tube, a shield intermediate said tuned circuits and connected to said grid, said shield having an aperture, and a selective feed back extending through said aperture and comprising an S-shaped conductor whose opposite halves are on opposite sides of said shield.

17. An ultra high frequency oscillator comprising a pair of vacuum tubes each having an anode, a cathode and a grid, a tuned circuit of substantially distributed constants connecting said anodes together, a tuned circuit of substantially distributed constants connecting said cathodes together, a metallic shield directly connecting said grids together, a direct connection from said shield to ground, means external of said tubes for shielding said tuned circuits from each other, and a selective feed back circuit coupling said two tuned circuits, said feed back circuit including a variable reactance for tuning the same to the frequency at which said oscillator should function.

18. An ultra high frequency oscillator comprising a vacuum tube having a cathode, an anode, and a grid, individual tunable resonant circuits for said cathode and anode, means external of said tube for shielding said resonant circuits from each other, a direct conductive connection from said shield to said grid, a tunable feedback loop magnetically coupling said tuned circuits together, and an adjustable stub tuner connected to the center of said loop.

19. An ultra high frequency oscillator comprising a vacuum tube having a cathode, an anode and a grid, individual tunable resonant circuits for said cathode and anode, means external of said tube for shielding said resonant circuits from each other, a direct conductive connection from said shield to said grid, a feedback loop magnetically coupling said tuned circuits together, and a reactance circuit coupling the center of said loop to said shield.
